WILLIAM W. RIDGELY, OF SYRACUSE, NEW YORK

AIR FEEDING SYSTEM FOR COAL BURNERS

Application filed October 3, 1930. Serial No. 486,157.

This invention relates to an air feeding system for coal and other solid fuel burners as commonly used in furnaces and boilers for heating purposes, and is particularly useful in the distillation of the gases from the cheaper grades of anthracite and bituminous coal and in the complete combustion of the gases immediately following the distillation.

10 The main object is to provide simple and efficient means adapted to be easily and quickly installed in old or new furnaces or boilers for effecting a more rapid and complete combustion of the fuel and thereby to render such combustion substantially smokeless.

One of the specific objects is to support the air distributing head within the combustion chamber in such manner that the inflowing air will be pre-heated and evenly distributed in fan-like jets over and upon the surface of the fuel, assuring a more complete and expeditious combustion of the gases immediately following the distillation thereof and thereby to reduce to a minimum the smoke content in the products of combustion escaping through the chimney or other flue.

In other words I have sought to concentrate and direct the inflowing air from the exterior to the surface of the burning fuel through substantially closed conduits passing from the underside upwardly through the fuel for pre-heating and pressure purposes, and to distribute the heated air evenly over the surface of the fuel for accelerating and maintaining the combustion of the liberated gases.

Another object is to provide simple and efficient means for concentrating and directing additional atmospheric air from the exterior through the fuel at different levels so as to accelerate the distillation of the gases from the coal.

A further object is to provide simple and efficient means for concentrating and directing the inflow of external air from the underside upwardly through the fuel grates and fuel thereon for further accelerating the distillation of the gases from the fuel.

Another object is to provide means, pref-

erably in the form of a fan or blower, projecting external air through the several conduits into and above the surface of the fuel for additionally accelerating the complete combustion of the fuel and gases. 55

Other objects and uses relating to specific parts of the apparatus will be brought out in the following description.

In the drawing:

Figure 1 is a vertical sectional view of a 60 portion of a heater and fuel grate, together with my improved air carbureting system, partly in elevation.

Figures 2 and 3 are perspective views of 65 the two plates forming the head or top of the carburetor system.

Figure 4 is a perspective view of the air distributing element located below the fuel grate.

Figure 5 is a perspective view of one of 70 the heat refractory tubes surrounding the adjacent portion of the main upright air tube within the body of fuel in the combustion chamber.

This air feeding and distributing system 75 may be installed in any furnace or boiler —A— having a combustion chamber —a— and an ash pit or lower chamber —a'— underlying the fuel grate —B— and comprising a main upright air tube —1— extending through a central opening —b— in the grate —B— above the level of the fuel as —C—.

The lower end of the central upright air conduit —1— is provided with a lateral extension —2— leading to the exterior of the heater —A— through an opening —a''— for connection with an external blower —3— or equivalent means for circulating the air 85 from the outside of the heater, upwardly 90 through the body of fuel —C—.

The upper end of the upright conduit —1— is operatively connected to a hollow air distributing head —4— which is closed at the top and is provided with circumferentially 95 elongated peripheral slots —5— for discharging the inflowing air in relatively thin fanlike jets over and upon the surface of the fuel or, rather, into the path of the distilled gases liberated from the fuel. 100

That is, the conduit —1— extends some distance through and above the grate —B— to about the level of the surface of a predetermined quantity of fuel therein, so that 5 the distributing head —4— will be disposed in a horizontal plane closely adjacent said surface.

The distributing head —4— is preferably composed of a pair of similar cup-shaped 10 sections —4'— and —4''— of considerably greater diameter than that of the upright tube —1— and arranged with their open sides facing each other, as shown in Figure 1, the meeting edges of said sections being 15 provided with a series of, in this instance three, relatively shallow bosses —6— projecting slightly beyond the remaining portions of the meeting edges of the sections to form the circumferential slots —5— when 20 the sections are resting one upon the other.

The lower section —4'— is provided with a central opening —7— communicating with the upper end of the pipe —1— and is also provided with a pendant hub —8— telescopically supported upon the upper end of 25 said pipe to permit the entire distributing head to be easily and quickly removed by upward displacement, or replaced at will.

The top of the upper section —4''— is 30 closed and is provided with a series of, in this instance three, threaded apertures 9 for receiving a corresponding number of adjusting screws —10— which engage the lower section —4'— and serve as a means for 35 adjusting the upper section relatively to the lower section for varying the vertical depth of the slots —5— as may be required to regulate the volume of air discharging therethrough, over the surface of the fuel.

40 It is now clear that when the heater is in operation, atmospheric air may flow from the outside of the heater, aided by the blower —3— if necessary, through the pipe —2— and thence upwardly through the vertical extension —1— of the pipe —2— and thence 45 upwardly through said pipe into the distributing head —4— from which it emerges through the radial slots —5— in all directions directly over the surface of the fuel.

50 During the transit of the air through the pipe —1— the air becomes pre-heated and enters the distributing head —4— in this pre-heated condition where it is additionally heated and allowed to discharge through 55 the slots —5— across the surface of the fuel to cause complete combustion of the gases which are liberated by the distillation of the coal and thereby to reduce to a minimum the smoke content of the escaping products 60 of combustion.

The opening —b— in the grate —B— through which the pipe —1— passes is of appreciably greater diameter than the external diameter of the pipe to allow the passage of 65 air from the underside of the grate or ash

box —a— through said opening to the overlying combustion chamber.

The grate —B— also permits the flow of air from the underside upwardly therethrough into the combustion chamber to additionally support the combustion of the fuel therein. 70

As previously stated, the pipe —1— extends some distance above the grate —B— to the overlying distributing head —4— 75 and the intervening space between the distributing head and top of the grate is utilized to receive a plurality of, in this instance three, tubular sections —11— of heat refracting material such as fire brick, said sections being arranged one above the other around the adjacent portion of the air pipe —1— to extend from the top of the grate —B— to approximately the underside of the distributing head —4— as shown in Figure 80 1.

The interior diameter of each section —11— is somewhat greater than the external diameter of the pipe —1— to form intervening air passages —12— communicating with each other and with the opening —b— through the center of the grate. 85

The opposite ends of each section —11— are provided with radial grooves or air passages —13— extending from the air passages —12— to the exterior thereof to allow the air to pass from the air passages —12— into the combustion chamber. 90

That is, the air from the blower —3— is free to pass upwardly through the openings —b— and passages —12— in the sections —11— and thence through the radial passages —13— into the combustion chamber for distribution through the fuel at different levels, thereby assisting in supporting 100 the combustion of such fuel and resultant distillation of the gas therefrom. 105

The lower horizontal extension —2— and lower end of the upright pipe —1— are enclosed in a secondary air pipe —14— of greater interior diameter than the exterior diameter of the pipe —1— and its extension —2— to form an intervening air passage —15—. 110

This pipe section —14— extends laterally through the opening —a''— in the heater shell —A— and is preferably connected to the blower —3—, the inner upright end of the pipe —14— being connected to a supplemental air distributing head —16— having a central opening —17— communicating with the passage —15—. 115

The distributing head —16— is supported upon the inner upper end of the pipe —14— just below the grate —B— and is provided with a plurality of, in this instance four, radially projecting branch pipes —18— communicating with the interior of the head —16— and their outer ends closed by suitable plugs —19—, the upper sides of said 120

pipes —18— being provided with perforations —20— to allow the air to escape upwardly therefrom and thence into the combustion chamber through the openings in the grate, as shown in Figure 1.

If desired, the top wall of the supplemental distributing head —16— may be provided with an air exit —21— communicating with the opening —b— in the center of the grate to allow air to pass from the pipe —14— upwardly through the opening —b— and thence into the passages —12— of the fire brick sections —11— and outwardly through the radial openings —13— into the combustion chamber at different levels to assist in the combustion of the fuel and resultant distillation of the gas therefrom.

As illustrated the supplemental head —16— is suspended from the lower grate 20 bar of the grate —b— through the medium of suitable hangers —22—, shown in Figure 1.

If desired, the upper inner end of the pipe —14— may be supported against downward movement by means of a pin —23— extending diametrically through registering openings in the adjacent portions of the head —16— assuring the concentric spaced relation of the adjacent portions of the pipes 25 —1— and —14—.

The outlet of the blower —3— is shown as provided with a damper —24— for regulating the amount of air delivered to the pipes —1— and —2— and incidentally regulating the amount of air entering the combustion chamber delivered to the distributing heads —4— and —16— and to the fuel 35 in the combustion chamber —a—.

The upper grate section —b'— is rotatable 40 relatively to the underlying portions of the grate and is provided with a hub extending downwardly through registering openings in the overlying grate sections, said hub having its lower end provided with a crank 45 arm —25— adapted to be connected in any suitable manner to an external operating member for operating the grate section —b'— angularly about its axis, when desired, without in any way disturbing the stationary positions of the pipes —1— and —14— and distributing heads —4— and —16—.

Operation

When a proper amount of fuel has been introduced into the combustion chamber and ignited, a certain amount of air will flow from the ash pit —a— upwardly through the grates and into the fuel in the combustion chamber, but owing to the fact that the air in the ash pit is then in a more or less cold condition its upward movement through the fuel for draft purposes is more or less sluggish and, in fact, this sluggish condition 60 obtains over all conditions of the fire in

the combustion chamber so that when the cheaper grades of coal, such as bituminous coal dust and anthracite buckwheat, is used, the natural draft from the ash pit through the fuel is insufficient to properly support 70 the combustion of the fuel.

I am aware that when this quality of fuel is burned in the usual heater, it has been necessary to use motor-driven fans or equivalent devices for forcing the air from the ash pit upwardly through the grates and thence through the fuel, but owing to the large volume of air usually present in the ash pits of the ordinary heaters it is necessary to use a correspondingly large blower 75 and a motor of sufficient power to drive the same, but by concentrating the volume of air used for combustion purposes and properly directing it into and upon the surface of the fuel in the combustion chamber as in my present air distributing system, I am unable to use a blower of extremely small size and a driving motor of correspondingly small power and for obtaining better combustion than would be possible under the ordinary blower system.

In fact, after the fuel has been sufficiently ignited to produce the desired distillation of the gases the blower may be disconnected and the air allowed to flow freely from the outside through the pipe —1— and into the upper distributing head —4—, thereby causing the air to be pre-heated in transit and to be forcibly ejected through the thin slots —5— and across practically the entire surface of the fuel under its own expansive force, thereby causing a complete combustion of the gases immediately upon their appearance at the surface of the fuel after distillation, resulting in a blue blaze of high 95 temperature extending over the entire area of the fuel surface and incidentally reducing to a minimum the smoke content of the escaping products of combustion.

It has been found that the arrangement 100 of the tubular sections —8— of fire brick or equivalent heat refracting material around the portion of the pipe —1— between the grate —b— and distributing head —4— causes said sections to become more or less incandescent when the fire is underway, thereby increasing the temperature of the air passing upwardly through the pipe —1— into the distributing head —4— and incidentally producing a more rapid and efficient 105 combustion of all the gases at the surface of the fuel immediately upon their distillation.

Furthermore, it has been found that the combustion of the fuel is accelerated by the lateral distribution of the air from the interior of the sections —8— into the fuel at different levels and that this influx of air 115 into the interior of the sections —11— is materially aided by the connection of the air supply pipe —14— thereto, particularly 120

under the pressure produced by the blower

—3.

It is now obvious that this complete combustion of the fuel and gases produces a maximum temperature in the combustion chamber and incidentally induces a more rapid escape of the smokeless products of combustion through the chimney or flue to assist the draft even though the flue may be unduly restricted in area from any cause.

What I claim is:—

1. An air feeding system for coal-burning heaters having a combustion chamber and an underlying air chamber, a fuel-supporting grate, an air feed pipe extending from the underside upwardly through and some distance above the grate, a distributor head mounted upon the upper end of the pipe and provided with an air chamber for receiving air from the pipe, said head having air exit openings leading from the chamber to the exterior of the head, and a tubular enclosure surrounding a portion of the pipe between the grate and distributing head in radially spaced relation thereto to form an intervening air chamber communicating with the combustion chamber and with the first named air chamber.

2. In an air feeding system for coal-burning heaters having a fuel-supporting grate provided with a central vertical opening therethrough, said system including a hollow distributing head supported some distance above the grate co-axial with said opening and provided with an air inlet opening in its underside and exit openings in its peripheral walls, an air conduit connected to the inlet opening of the distributing head and extended downwardly therefrom through the opening in the grate, and means for circulating air from the exterior of the heater through said conduit and distributing head, a tubular member surrounding the portion of the conduit between the distributing head and grate in spaced relation to said conduit to form an air passage therethrough communicating with the opening in the grate, and means for conducting air from the exterior of the heater to the opening in the grate for circulation through said opening into the tubular member.

3. An air feeding system for coal burning heaters having a grate, an air pipe extending from the underside upwardly through and above the grate, an air distributing head mounted on the upper end of the pipe, an additional air supply pipe surrounding the portion of the first named pipe below the grate and provided with an air distributing head underlying the grate.

In witness whereof I have hereunto set my hand this 30th day of September, 1930.

WILLIAM W. RIDGELY.
